UNITED STATES PATENT OFFICE.

LOUIS GOLDSMITH, OF ALTOONA, PENNSYLVANIA.

ELECTRIC SIGN.

Application filed February 18, 1928. Serial No. 255,353.

The present invention relates to improvements in signs and has for its principal object to provide a changeable exhibitor that includes a plurality of independently operable double real and webbed structures for association with a base plate having displaying openings, whereby various combinations of letters may be formed and displayed to constitute a complete sign.

Another important object of the invention is to provide a sign of the above mentioned character that includes a means for illuminating the various letters or characters arranged on the webs so that the sign can be easily read at night as well as in the day time.

A still further object is to provide an electric sign of the above mentioned character which is simple in construction, strong and durable, and further well adapted to the purpose for which it is designed.

Other objects and advantages of the invention will become apparent during the course of the following detailed description.

In the accompanying drawings, forming a part of this application and wherein like reference characters designate like parts throughout the views:

Figure 1 is a front elevation of the electric sign embodying my invention.

Figure 2 is a vertical sectional view therethrough.

Figure 3 is a sectional view, taken approximately on the line 3-3 of Figure 2, looking in the direction of the arrows.

Figure 4 is a top plan view of the sign.

Figure 5 is a detail view of one of the vertical brackets showing the spool supporting members carried thereby.

Figure 6 is a view taken at right angles with respect to Figure 5 and showing the relation of the bracket with respect to the frame, and

Figure 7 is a detail view of one of the spools or reels.

In the drawings, wherein for the purpose of illustration is shown the preferred embodiment of my invention, the numeral 1 designates a substantially rectangular shaped casing which is open at its front side, the sides as well as the top and bottom of the casing tapering toward the rear wall 2 as is clearly shown in Figures 2 and 4 of the drawings. A substantially rectangular shaped flange cover 3 has the free edge portion of the flange thereof reduced

for disposition within the open front side of the casing 1 as illustrated at 4, in Figure 2 and the shoulder formed at the juncture of the reduced portion 4 with the main flange portion abuts the forward rolled edge of the casing in the manner as also shown more clearly in Figure 2.

For the purpose of positively securing the flanged cover 3 on the casing, I provide the pivoted hooks 5 on the sides of the flanged cover and these hooks engage over laterally extending headed pins 6 that project from the opposite sides of the forward edge portion of the casing.

The front face of the flanged cover 3 is formed with a series of substantially rectangular shaped displaying openings 7 that are arranged in a predetermined manner, and the purpose of these openings will be presently described.

Secured within the flanged cover 3 is the wooden frame 8 and this frame is of such width as to extend between the apertured face of the cover and the shoulder formed by the reduced portion 4 of the flange of the cover as is clearly shown in Figure 2. The forward edges of the vertical sides of this wooden frame 8 are formed with the vertically spaced aligned notches 9 and the purpose thereof is to provide a support for the horizontally extending rods 10, which rods extend for the full length of the frame and it is to be observed that the notches are so arranged as to cause the rods to be disposed directly adjacent the upper and lower edges of the openings 7 formed in the front face of the cover 3.

A plurality of parallel spaced flat metallic strips designated by the numeral 11 are arranged vertically within the wooden frame 8, each strip constituting a bracket and being formed at its upper and lower ends with the laterally disposed portions 12 that are secured to the upper and lower members of the wooden frame 8 by any appropriate fastening means. The vertical brackets or strips 11 are so spaced with respect to each other as to be disposed on opposite sides of the vertically aligned displaying openings 7 formed in the front face of the cover 3. Furthermore, the forward edges of these vertical strips or brackets are spaced from the front face of the cover so as to permit the horizontal rod 10 to extend across the forward edges of the strips as shown in Figure 2. Each of the strips

or brackets is cut out at the rear edge portion thereof at vertically spaced intervals, as illustrated at 13, for a purpose to be presently described.

- 5 Secured on opposite sides of each of the vertical brackets 11 are the spring steel strips 15, the intermediate portions of these spring steel strips being secured to the vertical brackets so that the ends of the strip 10 extend into the cut out portions 13 and furthermore the ends of the spring steel strips are flexed outwardly slightly and formed on the outer free ends of each spring steel strip is the circular bolted head 16, the 15 same being formed with a pintle receiving opening. The manner in which these spring steel strips 15 are associated with the vertical brackets 11 is clearly shown in Figures 2, 5, and 6 of the drawings.
- 20 A series of relatively small spools or reels such as shown at 17 are formed with the pintles 18 that are rotatably mounted in the openings provided therefor in the upper and lower ends of each pair of opposed spring 25 steel strips 15, so that upper and lower pairs of reels or spools are provided.

A web formed of paper, or any other suitable material and having the various letters of the alphabet printed on the outer face thereof is secured at one end on the 30 uppermost spool or reel of each pair and this web 19 extends over the rods 10 for disposition against the inner face of the apertured side of the cover 3 and the other end of the 35 web is secured on the lower spool or roller of each pair. The web is unrolled from the upper roller or spool and is wound around the lower spool or reel of each pair by manually actuating the spools when the 40 cover 3 is removed from the casing 1 and the cover is laid flat on a surface or may be disposed vertically and access to the rollers or spools being had from the rear side of the said frame and the cut-out portions 13 45 provide sufficient space whereby the spools may be properly grasped for turning the same.

This construction provides a means whereby various letters may be displayed through 50 the openings 7 to form various combinations of words for display purposes, and by providing a large number of openings 7 in the front face of the cover 3 and complementary double wheel and web structures in the rear

of each opening, the sign may be employed 55 for displaying a considerable amount of advertising.

An electric lamp 20 is arranged within the casing 1 in a suitable socket provided therefor and is secured to the rear wall 2 of 60 the casing, and any appropriate means may be provided for causing the intermittent flashing of the light. The lamp will properly illuminate a sign so that the same can be viewed at night and by simply disengaging the hook 5 from the headed pins 6, the cover 3 may be removed from the casing to permit the changing of the combination of words as may be desired.

An electric sign of the above mentioned 70 character may be manufactured at a very low cost, owing to its simplicity and the sign can be changed from time to time without necessitating loss of any considerable amount of time or labor.

75 While I have shown the preferred embodiment of my invention, it is to be understood that various changes in the size, shape and arrangement of parts may be resorted to without departing from the spirit of the 80 invention or the scope of the appended claim.

What I claim is:

In a sign, a frame, a face plate at the front of the frame provided with displaying 85 openings, a plurality of parallel spaced brackets arranged vertically in the frame on opposite sides of the aligned displaying openings, spring strips secured on opposite sides of the bracket and arranged in pairs, the free ends of the spring strips being 90 flexed, upper and lower rotatable reels supported between each pair of spring strips above and below the displaying openings, an indicia carrying web operatively connected at the ends to the upper and lower reels of 95 each pair, said web adapted to extend over the respective displaying openings, means for maintaining a portion of the web against the rear side of the face plate, said last mentioned means comprising a series of horizontally arranged rods extending across the 100 vertical brackets directly above the upper and lower edges of the displaying openings and engaging with the inner side of the webs.

105 In testimony whereof I affix my signature.

LOUIS GOLDSMITH.
